UNITED STATES PATENT OFFICE.

CHARLES M. LEVY, OF NEW YORK, N. Y., ASSIGNOR TO CHARLES M. LEVY & SON, OF NEW YORK, N. Y., A COPARTNERSHIP COMPOSED OF CHARLES M. LEVY, AND NORMAN C. LEVY.

FLEXIBLE CHAIN.

1,426,884.

Specification of Letters Patent. Patented Aug. 22, 1922.

Application filed May 21, 1921. Serial No. 471,303.

To all whom it may concern:

Be it known that I, CHARLES M. LEVY, a citizen of the United States, and resident of the borough of Manhattan, in the county of New York, city and State of New York, have invented certain new and useful Improvements in Flexible Chains, of which the following is a specification.

This invention relates to improvements in flexible chains especially adapted for use in jewelry, for instance for bracelets and the like.

One of the main objects of the invention is to provide a flexible chain in which the links are made up of two series of arch-shape members, one of which forms the outer surface of the chain and the other forms the inner surface thereof, said arches being arranged with their arms extending 20 in opposite directions and flexibly connected together.

There are other important objects and advantages of the invention which will more fully hereinafter appear.

25 In the drawing:

Fig. 1 is a face view of the outer side of the chain, partly in section;

Fig. 2 a face view of the inner side of the chain;

30 Fig. 3 a side elevation showing the chain flexed in full lines and straight in dotted lines;

Fig. 4 a transverse sectional view taken on the line 4—4 of Fig. 1;

35 Fig. 5 a detail perspective view of one of the outer links;

Fig. 6 a detail perspective view of one of the inner links;

40 Fig. 7 a detail view of the blank from which the outer links are made;

Fig. 8 a detail view of the blank from which the inner links are made;

45 Fig. 9 a perspective view of the blank forming the inner links, partly shaped; and

Fig. 10 a view similar to Fig. 9 showing the blank ready for assembling in the chain.

The chain is made up of two sets of arch-shape links 1 and 2, the arches 1 forming the outer face of the chain and the arches 2 50 forming the inner face thereof. Each of the links 1 comprises the outer or face member 3 and the two side members 4. The side members are preferably bent at right angles to the outer face member and are each 55 perforated at 5. These links 1 of the chain are

arranged side by side and close together so that the joints between them run transversely of the chain, the side members forming portions of the sides of the chain. The side members are slightly tapered from the 60 face member 3 so that the free ends thereof are slightly narrower than the ends join to said face member. The inner links 2 are formed with the inner body member 6 and the side members 7 which extend in the same 65 direction from the ends of the body member 6 and which are bent at right angles to said body member. The side members 7 receive between them the side members 4 of the outer links. The body members 6 are 70 arranged side by side so that the joints between them run transversely of the chain; and they are arranged a slightly greater distance apart than the outer links of the chain, so that the chain will flex toward the inner 75 links and away from the outer links, the spaces between the body members of the inner links permitting the flexing of the body of the chain. The outer or face members of the links 1 are arranged close together, practically in contact so that when the chain is flexed the spaces between the face members of the links will be very 80 slight. The tapered side members 4 of the outer links permit the chain as a whole to be flexed toward the inner links. Because of this taper there will be a slight space between the free ends of the adjacent side members 4, which space will be taken up and closed when the chain is flexed. This is 85 clearly illustrated in the sectional part of Fig. 3. By this means the face members of the outer links may be placed directly in contact with each other and will remain in contact with each other even when the chain 90 is flexed toward the inner links 2.

Each of the side members of the inner links 2 is formed with two inwardly extending lugs 8. The inner links are arranged to break joints with the outer links, 100 so that the joints between the inner links will be directly opposite the solid outer face members 3 of the outer links 1. The side members 7 bridge the joints between the side members 4 of the outer links. The 105 lugs 8 of each side member 7 pass through the perforations 5 of the two adjacent side members 4, so that each of the inner links 2 is connected to two of the outer links 1 and each of the outer links 1 is connected to 110

two adjacent inner links 2. The inner ends of the lugs 8 are bent laterally and clinched on the inner sides of the side members 4 of the outer links to permanently connect 5 all of the links together. The side members 4 of the outer links fit within the side members 7 of the inner links, the two sets of side members forming the complete side of the chain.

10 Each link of the outer series is made from a blank 9, shown in Fig. 7. This blank is perforated near its ends, as shown in said Fig. 7, and is then bent into arch shape, as shown in Fig. 5, the two perforated 15 tapered end pieces then forming the side members of the link. Each link of the inner series is formed from a blank 10, shown in Fig. 8. This blank is first bent to form the connecting lugs 8, as shown in Fig. 9. 20 The blank is then bent, as shown in Fig. 10, to partly form the side members 7. In this form the inner links are assembled with the outer links, and the side members 7 are then finally bent to permanent form, and 25 the lugs 8 are caused to enter the perforations 5 of the side members of the outer links. The inner ends of the lugs 8 are then bent laterally to clinch the outer links to the inner links and to complete the chain. 30 It is manifest that the flexible chain is made up of two sets of links which overlap and are flexibly connected together, so that the complete chain is a rectangular tube made up of articulated or connected arch- 35 like links whose side members embrace each other and are flexibly connected together. It is also manifest that the joints between the outer links are lapped by the body parts of the inner links so that whether the chain 40 is straight or flexed there is no appearance of openings through the chain, either through the sides or through the top and bottom.

A chain made up as described is very 45 pleasing in appearance; is simple to manufacture for the reason that only two stampings are used and these are connected together without the use of solder and without the use of any fastening means except 50 the links themselves. Such a chain is especially adapted for use in jewelry, and may be made up into bracelets of very pleasing appearance, and at the same time very durable and cannot be broken except by 55 unusually rough treatment.

What I claim is:

1. A flexible chain comprising a series of arch-shape outer links, a series of arch-shape inner links, the side members of said links 60 extending in opposite directions and overlapping to form the sides of the chain, and each of the outer links being connected to two adjacent inner links.

2. A flexible chain comprising a series of 65 arch-shape outer links, a series of arch-shape

inner links, the side members of said links extending in opposite directions and overlapping to form the sides of the chain, each of the outer links being connected to two adjacent inner links, and the inner links being spaced farther apart than the outer links to permit the chain to flex toward its inner side. 70

3. A flexible chain comprising a series of arch-shape outer links, a series of arch-shape inner links, the side members of the outer links extending toward the inner links, the side members of the inner links extending in the opposite direction and toward the outer links, the side members of one series of links fitting within the side members of the other series of links to form the sides of the chain, the links of one series breaking joints with the links of the other series, and integral connecting lugs 85 formed on the side members of one series of links and connected to the side members of the other series of links. 75

4. A substantially rectangular tubular flexible chain comprising two series of sheet metal links, one forming the outer face of the chain and the other the inner face thereof, and connecting lugs formed on the ends of the links of one series and adapted to enter perforations at the ends of the links of the other series to form the complete tubular chain, each link of one series being connected to two adjacent links of the other series. 90

5. A substantially rectangular tubular flexible chain comprising a series of arch-shape outer links each formed with an outer or face member and two side members bent at right angles to the face member, a series of arch-shape inner links each formed with an inner body member and two side members 100 which extend in the same direction from the ends of the body member and at right angles to said body member, the side members of the outer links fitting against the inner sides of the side members of the inner links, a pair 110 of connecting lugs formed on each side member of the inner links and adapted to enter perforations in the side members of two adjacent outer links, the inner body member of the inner links being arranged a slightly 115 greater distance apart than the outer face members of the outer links whereby the chain may be flexed toward the inner links. 105

6. A substantially rectangular tubular flexible chain comprising a series of arch-shape outer links each formed with an outer or face member and two side members bent at right angles to the face member and tapered toward their free ends, a series of arch-shape inner links each formed with an inner body member and two side members which extend in the same direction from the ends of the body member and at right angles to said body member, the side members of the outer links fitting against the inner sides 120 125 130

- of the side members of the inner links, a pair of connecting lugs formed on each side member of the inner links and adapted to enter perforations in the side members of two adjacent outer links, the inner body member of the inner links being arranged a slightly greater distance apart than the outer face members of the outer links whereby the chain may be flexed toward the inner links.
- 10 7. A flexible chain comprising a series of arch-shape outer links each formed with an outer or face member and two side members bent at right angles to the face member and arranged side by side in channel formation
15 and having their side members apertured,
- and connecting links bridging the joints between the side members of the outer links, each of said connecting links being formed with lugs extending through the apertures in the side members of adjacent outer links, 20 said lugs being bent laterally and clinched within the channel formed by the outer links the side members of each outer link being flexibly secured to the side members of adjacent outer links by two of said connecting 25 links.

In testimony whereof I hereunto affix my signature.

CHARLES M. LEVY.
